HOG FEEDER

Max L. Rysdon and Richard C. Moyer, Sioux Falls, S. Dak.; said Moyer assignor to said Rysdon

Application April 29, 1950, Serial No. 159,068

3 Claims. (Cl. 119—53)

1

This invention relates to a hog feeder.

As is generally known, a hog feeder consists in a container having an open top for the insertion of the feed, and the feed gravitates downwardly into a trough that opens to the exterior from which the animals feed. The feed fed to animals in such a feeder is normally in dry form.

An object of the present invention is the provision of a novel construction hog feeder in which bridging of the feed as it gravitates downwardly is eliminated.

A second object of the invention is the provision of a hog feeder having such a novel construction that not only is bridging of the feed prevented, but a great saving of material is effected in the construction of the feeder.

More specifically, and in connection with the elimination of bridging of the feed, the feeder consists of a construction having side walls that taper outwardly in a downward direction, whereby bridging of the feed is eliminated. We have found that vertical and parallel side walls do not prevent bridging of the feed. There is a critical angle of the side walls by reason of the use of which bridging is eliminated and maximum capacity is attained; we have devised a hog feeder having such a novel construction that such critical angle is employed.

The hog feeder is fabricated from sheet metal. Sheet metal is supplied by a mill in certain standard widths, usually of an even number of inches in width; if sheets are required that are not of those standard widths, there are serious disadvantages.

Therefore, another specific object of the present invention is the provision of a novel hog feeder as referred to above having the advantages mentioned, and so constructed that standard mill width sheets can be employed with a minimum of wastage of material.

With these and other objects in view, our invention consists in the construction, arrangement, and combination of the various parts of our device whereby the objects contemplated are attained, as hereinafter more fully set forth, pointed out in the claims, and illustrated in the accompanying drawings, wherein:

Figure 1 is a side elevational view of the hog feeder of the present invention;

Figure 2 is a top view of the feeder with the cover removed;

Figure 3 is an enlarged vertical sectional view taken on line 3—3 of Figure 1;

Figure 4 is an end view of the feeder;

Figure 5 is a partial sectional view on an enlarged scale, taken on line 5—5 of Figure 4;

2

Figure 6 illustrates a mill sheet indicating in dotted lines, templates to be cut therefrom for forming certain elements of the feeder;

Figure 7 is one of the templates cut from the sheet of Figure 6, showing the bend lines;

Figure 8 illustrates a mill sheet on which is indicated in dotted lines, templates to be cut therefrom for forming other elements of the feeder; and

Figure 9 illustrates a template cut from the sheet of Figure 8, showing the bend lines.

Referring now in detail to the drawings, the feeder as a whole is shown in Figure 1 and referred to by the numeral 12. For purposes of convenience, a general description of the feeder is here given for the purpose of characterizing the general nature of the feeder as a whole, after which specific descriptions of the various elements will be given in detail.

The feeder 12 includes a bottom element 14 made up of two plates 16 supported on base elements 18. The sheets 16 have inclined portions overlapping at apex 20 and depressed portions 22 terminating in upturned portions 24. The depressed portions 22 form troughs extending the length of the feeder and are closed by covers 26. The numeral 28 indicates end walls made up of bottom plate members 30 and top plate members 32. The feeder also includes side walls indicated generally at 34, made up of plate members 36 and 38. The numeral 40 indicates a removable cover for closing the open top of the feeder.

Feed is inserted in the feeder through the open top and it gravitates downwardly into the troughs 22, from which animals feed upon raising of the covers 26. The feed usually fed to animals in the feeder is in dry form, often consisting of ground grains together with commercial feeds. The feed is thus usually in substantially powdered form, but may be granular. Such feed is apt to bridge between those walls of the feeder that are positioned relatively close together.

The plate members 30 of the end walls 26 are cut from a mill sheet, as indicated in Figure 8. The mill sheet is referred to at 42 and the dotted lines 44 indicate the cutting lines from which templates indicated at 46 in Fig. 9 are cut. The mill sheet illustrated is of standard width, its dimensions being 36" wide, and 96" long. These dimensions are only examples, but have a bearing on the sizes of other sheets from which other elements of the feeder are formed. In the template illustrated in Figure 9, the dot-dash lines 48 indicate bend lines for forming flanges for securing in place the piece which evolves into the plate member 30. The flanges formed by

bending on the lines 48 are, of course, turned at right angles to the plate member. The flange 50 thus formed on the bottom is fitted under the depressed portions 22 of the bottom member 14 and secured thereto as by spot welding or riveting. Similarly, the flanges 52 are secured to the upturned portions 24. The flanges 54 are rolled into tubular shaped elements as indicated at 54 in Figure 2. The plate members 36 are rectangular pieces having flanges 56 at their ends for securing to the end plate members 30, and down-turned flanges 58 at their upper edges for securing to the plate members 38. The plate members 36 converge in a downward direction and their bottom edges are spaced apart from each other, as well as being spaced from the apex 20 of the bottom member 14. The feed flows through openings formed by such spacing into the troughs 22. The central inclined portions 16 deflect the feed out into the troughs and 20 prevent the accumulation of feed in the center that would otherwise be unavailable to the animals.

Partition members 60 are placed in the troughs 22, these partition members being vertically disposed and spaced longitudinal of the troughs; they may be secured in position by forming flanges on the appropriate edges for securing to the adjacent elements of the feeder. The covers 26 are hingedly mounted in position by 25 means of extensions 62 shown best in Figure 1, having slots 64 forming end insert portions fitted in looped brackets 66, welded or otherwise secured to the plate members 36. The end portions of the extensions 62 are free to pivot in the brackets 66 and the covers 26 are thereby free to be swung upwardly.

Slide closure members 68 are provided for closing off the openings into the troughs. These closure members are in the form of plates abutting the inside surfaces of the plate members 36 and adapted to be slid up or down, being held in place by clamping brackets 70. The closure members 68 can be opened or closed to any desired degree for controlling the rate of flow of feed into the troughs. Figure 5 illustrates in detail how the closure members 68 are mounted. Partitions 72 may be interposed at desired positions in the feeder.

The upper portion of the feeder and its specific construction, together with the end plate members 30, constitute the subject matter of the present invention. It will be noted that the plate members 38 diverge in a downward direction and the particular angle that these plate members are disposed is a critical angle with respect to the results accomplished.

The plate elements 32 are cut from a mill sheet as indicated in Figure 6. The mill sheet here illustrated is approximately 96 inches long and 28 inches wide. It will be obvious, of course, that these dimensions are merely exemplary, and we do not wish to be limited to such specific measurements. However, there is a proportioned relationship between the size of the feeder and widths of mill sheets employed in the construction thereof. The dotted lines 76 indicate the lines for cutting the templates for forming the end plate members 32. The numeral 78 in Figure 7 shows a template cut from the mill sheet of Figure 6. The dot-dash lines 80 on the template 78 in Figure 7 indicate bend lines for forming flanges on the template in the formation of the end plate element 32, which are turned at right angles to the body of the template. The

flanges 82 are abutted against the side plate elements 38 and riveted or welded thereto. The flange 84 at the top is bent over and has a rebent portion for forming a reinforcement at the top. The bottom marginal portion indicated at 86 is not bent to form a flange but is fitted flat against the upper marginal portion of the bottom end plate member 30 and riveted thereto. The plate members 30 and 32 thus form the end walls of the feeder.

The plate members 38 are rectangular sheets, each having a looped portion 88 which is hooked under the down-turned flange 58 on the plate member 36. The top marginal edge of the plate member 38 is inturned to form a flange 90 for reinforcement purposes.

The cover 40 is formed of a rectangular sheet, the lateral edges of which are turned in as indicated at 92. The sheet forming the cover is preferably arcuate and end members 94 are secured thereto by any convenient means such as spot welding. Secured to each end member 94 is a link 96 pivoted at 98 and adapted to extend downwardly. Each link has a slot 100 for receiving a bolt 102 extending through a hole in the plate member 32, the bolt having a winged nut 104. Tightening the nuts 104 retains the cover in position and the cover can be moved to open position by loosening the nuts, lifting the cover up and swinging it to the side.

The plate elements 38 forming the upper portions of the side walls are disposed at an angle of 79° with the horizontal. We have found that when the plate elements are disposed at such an angle, there is no bridging of the feed between the side walls, as the feed gravitates downwardly through the feeder. We have also found that if the angle is 80° instead of 79°, there is a tendency to bridge, and if the angle is over 80°, bridging definitely occurs. On the other hand, if the angle referred to is less than 79°, bridging is still eliminated but capacity is sacrificed. For example, 75° would prevent bridging, but because the upper edges of the side walls would be so close together there would be considerably less capacity of the feeder. We believe that our invention includes any angle such as to prevent bridging of the feed, but we prefer to employ the angle of 79°, thus preventing bridging and providing the greatest capacity possible. As far as we are able to determine, our feeder is the first in which bridging is prevented without the use of a mechanical agitator. Bridging between the end walls of the feeder is prevented because of their greater spacing.

The second major object and advantage of the present invention is the elimination of waste material. The above description refers to the chief advantage, namely the prevention of bridging of the feed, and the prevention of waste material is particularly significant when considering the fact that the construction also prevents bridging.

As mentioned above, the end plate elements 32 are cut from a standard size mill sheet. The templates are cut from the mill sheet in successively reversed position; that is, the small end of one template is adjacent the large end of the next one. The fact that the side edges of the templates 78 are disposed at 79° permits a given number of templates to be cut from a standard size mill sheet, as illustrated in Figure 6, with the extremities of the outermost templates substantially in register with the end marginal edges of the sheet. If the angle is different from 79°, there is a wastage of material because any multi-

ple number of templates do not correspond to the length of a single mill sheet.

Also, because of the fact that an angle of 79° is employed, the side plate elements 38 result in standard mill sheet widths. For example, when the template 78 is cut from a mill sheet 74 of 28" in width, the side plate member 38 is substantially 28" wide, namely 28" in slant height. If the angle of the plate elements 38 is altered from 79°, the slant height of the plate elements must be increased or decreased, resulting in the necessity of employing a plate that is not a standard width. In the latter case, either there is wastage of material when the piece is cut from a wider sheet, or it is necessary to employ sheets that are not standard in width, with attendant difficulties. In addition, the particular construction enables the end plate members 30 to be cut from standard width sheets, with a minimum of wastage of material.

We have also found that when an angle of 79° is employed, the cover 40 can be fabricated from a standard width mill sheet. If an angle other than 79° is employed, the same conditions exist in connection with the cover 40 as just referred to in connection with the plate elements 38.

It is highly desirable in fabricating such device as the hog feeder herein disclosed to employ metal sheets of standard widths as supplied by a mill. If odd size sheets are employed, it becomes necessary to order at a time much in advance of the time for ordering standard size sheets, because steel mills cannot supply odd size sheets as quickly as standard width sheets. It is difficult to predict market conditions so far in advance, and if too great a quantity of odd size sheets are ordered and not used, they can not be readily resold. The purchaser then has inventory difficulties, while if he orders standard size sheets and finds later that he does not need as many as ordered, he can readily resell them. On the other hand, if odd size sheets are required, and standard sheets of greater dimensions than that required are ordered, then there is an objectionable wastage of material. The advantages of the present invention, in order to be properly emphasized, bear repetition, namely (a) a construction of a hog feeder wherein bridging of the feed as it gravitates downwardly is eliminated, and (b) a construction so designed that a great number of its elements are fabricated from standard size mill sheets.

While we have herein shown and described a preferred embodiment of our invention, manifestly it is susceptible of modification and rearrangement of the parts without departing from

the spirit and scope thereof. We do not, therefore, wish to be understood as limiting the invention to the precise form herein disclosed, except as we may be so limited by the appended claims.

5 We claim as our invention:

1. In a feeder of the character disclosed, a container having end walls and opposed upper side walls each inclined outwardly and downwardly at an angle of between 75° and 80° with the horizontal, opposed lower side walls inclined downwardly and inwardly, said upper side walls extending over the major portion of the height of said container and adapted to have feed stored in the space therebetween, the lower edges of said lower side walls being spaced apart to form a feed aperture extending along the length of said lower walls, a feeding trough extending along the length of each lower side wall and adapted to receive feed from said container, each feeding trough having a longitudinal wall inclined upwardly forming the back wall of said trough and cooperating with the back wall of the other trough to form a divider ridge extending the length of said feed aperture, and said back wall of each trough being spaced from the lower edge of the associate lower side wall to form a trough feed aperture through which feed is adapted to pass from the container into the troughs.

20 2. A feeder as set forth in claim 1 wherein the downward projection of the lower side walls intersect the upwardly inclined back walls of the troughs, and including closure members adjustably mounted on said lower side walls and slideable toward and away from the associate back walls of the troughs to vary the size of the trough feed apertures.

25 3. A feeder as set forth in claim 1 wherein the major portion of the upwardly inclined back wall of each trough extends from said divider ridge laterally outward of the lower edge of the adjacent lower side wall, whereby the feed passing through said feeding aperture moves laterally into the associate trough a substantial distance from said feeding aperture.

40 MAX L. RYSDON.
